(57) CLAIM

The ornamental design for a contoured mouse for a gaming device, as shown and described.

DESCRIPTION

FIG. 1 is a rear and left perspective view of a contoured mouse showing our new design;

FIG. 2 is a left side view thereof;

FIG. 3 is a right side view thereof;

FIG. 4 is a top view thereof;

FIG. 5 is a bottom view thereof;

FIG. 6 is a front view thereof;

FIG. 7 is a rear view thereof; and,

FIG. 8 is a front and right perspective showing illumination at finger wheel in a position of use.
